(57) **CLAIM**

The ornamental design for a pin pad with integrated scanner, as shown and described.

DESCRIPTION

FIG. 1 is a front view of a pin pad with integrated scanner thereof;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front top right perspective view thereof;

FIG. 8 is a front top left perspective view thereof;

FIG. 9 is a front bottom left perspective view thereof;

FIG. 10 is a front bottom right perspective view thereof;

FIG. 11 is a rear bottom left perspective view thereof;

FIG. 12 is a rear bottom right perspective view thereof;

FIG. 13 is a rear top left perspective view thereof; and,

FIG. 14 is a rear top right perspective view thereof.

The broken lines illustrate features of the article that form no part of the claimed design.
